Primary Examiner — Jae Liang(74) *Attorney, Agent, or Firm* — Law Offices of Steven W. Weinrieb(57) **CLAIM**

The ornamental design for a straw lid, as shown and described.

DESCRIPTION

FIG. 1 is a front, right side, top perspective view of a straw lid showing my new design;

FIG. 2 is a rear, left side, bottom perspective view thereof;

FIG. 3 is a front elevational view;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is a front, right side, top perspective view thereof with the straw holder implement of the straw lid shown in its closed position.

The broken lines immediately adjacent to the claimed portions are boundaries, all other broken lines are environmental structures; all the broken lines form no part of the claimed design.

1 Claim, 9 Drawing Sheets(56)
